UNITED STATES PATENT OFFICE

HARRY SHACTER, OF NEW YORK, N. Y., ASSIGNOR TO ASSOCIATED MERCHANDISING CORPORATION, OF NEW YORK, N. Y., A CORPORATION OF NEW JERSEY

DESIGN FOR AN ENSEMBLE DRESS

Application filed September 13, 1932. Serial No. 44,825. Term of patent 3½ years.

To all whom it may concern:

Be it known that I, HARRY SHACTER, a citizen of the United States, and resident of 662 Madison Avenue, New York city, in the county of New York and State of New York, have invented a new, original, and ornamental Design for an Ensemble Dress, of which the following is a specification, reference being had to the accompanying drawing, forming part thereof.

I claim:

The ornamental design for an ensemble dress substantially as shown.

HARRY SHACTER.
